Victor J. Evans

ATTORNEY.

UNITED STATES PATENT OFFICE.

HANS SORENSEN, OF HARDY, IOWA.

SHADE-ROLLER.

1,399,812.

Specification of Letters Patent. Patented Dec. 13, 1921.

Application filed September 27, 1919. Serial No. 326,743.

To all whom it may concern:

Be it known that I, HANS SORENSEN, a citizen of the United States, residing at Hardy, in the county of Humboldt and State 5 of Iowa, have invented new and useful Improvements in Shade-Rollers, of which the following is a specification.

This invention relates to curtain or shade 10 rollers and has for its object the provision of a shade roller provided with means whereby a shade may be detachably secured thereto without the use of tacks or similar fastening members, the improvement being in the provision of means engaging the roller 15 and the shade for holding the shade in position.

An important object is the provision of a roller of this character which will be simple and inexpensive in manufacture, highly 20 efficient in use, durable in service, and a general improvement in the art.

With the above and other objects and advantages in view, the invention consists in the details of construction to be hereinafter 25 more fully described and claimed, and illustrated in the accompanying drawings in which—

Figure 1 is an elevation of a shade roller showing a shade thereon held by my device, 30 Fig. 2 is a cross sectional view on the line 2—2 of Fig. 1,

Fig. 3 is a cross sectional view on the line 3—3 of Fig. 1,

Fig. 4 is an end elevation, and

Fig. 5 is an elevation of the roller with the shade removed.

Referring more particularly to the drawings, the letter A designates a shade roller of ordinary construction and B designates a 40 shade.

In carrying out my invention I provide a roller A with a longitudinally extending groove 10 which extends entirely to one end thereof and which extends beneath the ferrule C at the other end. Disposed upon the end unprovided with the ferrule is a plate 45 11 pivotally mounted by means of the usual lug D provided on a shade roller and having an extension 12 adapted to register with and close the end of the groove 10. Disposed at spaced intervals within the groove 50 10 are guide members 13 which, in the pres-

ent instance, are shown as screw eyes which are so arranged as to be disposed transversely of the groove.

The shade B has its ends hemmed, as shown at 14, and has the edge of the hem provided with notches 15. I also make use of a wire rod 16.

In assembling the shade and roller, the 60 hem 14 on the shade is placed against the roller A with its edge disposed within the groove 10 and with the notches 15 arranged at the screw eyes 13. The disk 11 being rotated so that the extension 12 will be in non-obstructing relation to the groove 10, the operator then grasps the rod 16 and inserts it through the hem, through the screw eyes 13, and shoves it throughout the length of the groove 10 so that its end will engage beneath the ferrule C. After this is done the 65 disk 11 is partially rotated to bring the extension 12 in alignment with the end of the groove 10 to form an end closure therefor for preventing longitudinal movement of 70 the rod 16.

From the foregoing description and a study of the drawings it will be apparent that I have thus provided very simple and efficient means for attaching a shade to its 80 roller without the use of tacks or similar securing means, my specific means being easily detachable without consuming any great degree of time and without liability of injuring the shade.

While I have shown and described the preferred embodiment of my invention, it is of course to be understood that I reserve the right to make such changes in the form, construction, and arrangement of parts as 90 will not depart from the spirit of the invention or the scope of the subjoined claim.

Having thus described my invention, I claim:

In combination, a shade roller provided 95 in one side with a longitudinal groove, a fixed ferrule at one end of the roller extending permanently over said groove, a disk pivoted upon the other end of the roller and having a radially extending lug adapted to 100 register with and form an end closure for the other end of said groove, a plurality of guides located at spaced intervals within said groove and arranged transversely there-

of, a shade having one end hemmed and disposable within said groove, said hem being notched at intervals for the accommodation of said guides, and a rod slidably longitudinally of said groove and insertible through said hem and through said guides with one end of the rod engaging beneath

and retained in position by said ferrule and said disk being rotatable whereby to bring the lug thereof into engagement with the other end of said rod to prevent longitudinal movement thereof.

In testimony whereof I affix my signature.
HANS SORENSEN.
